INFLATABLE SLED

Randolph L. Frank, 34808 Farragut,
Westland, Mich. 48185

Filed Dec. 11, 1970, Ser. No. 26,424

Term of patent 14 years

Int. Cl. D21—02

U.S. Cl. D34—15

FIG. 1 is a top plan view of an inflatable sled embodying my new design, shown in an inflated condition.

FIG. 2 is a front elevational view, taken on plane 2—2 in FIG. 1.

FIG. 3 is a bottom plan view, taken on plane 3—3 of FIG. 2.

FIG. 4 is a side elevational view, taken on plane 4—4 of FIG. 1.

FIG. 5 is a sectional view, taken on plane 5—5 of FIG. 1.

I claim:

The ornamental design for an inflatable sled, as shown and described.
